PHONOGRAPH

Heinrich F. Max Gramann, Orange, N. J., assignor to Thomas A. Edison, Incorporated, West Orange, N. J., a corporation of New Jersey

Application May 7, 1935, Serial No. 20,126

6 Claims. (Cl. 274—30)

This invention relates to phonographs, and more particularly to phonographs adapted to serve both recording and reproducing functions. While not limited thereto, the invention particularly contemplates business phonographs of the type primarily adapted for the recordation and reproduction of dictation.

It is an object of the invention to provide an improved phonograph readily convertible between conditions appropriate to recordation and reproduction, respectively.

Another object is to safeguard the record and parts of the phonograph, particularly when the latter is adjusted for reproduction, against accidental damage.

Still another object is the provision of an improved sound conducting system appropriate to the convertible nature of the phonograph.

Other and allied objects will more fully appear from the following description and the appended claims.

In the description hereinafter set forth reference is had to the accompanying drawings, in which:

Figure 1 is a partial plan view, partly broken away, of a phonograph according to my invention, the instrument being shown adjusted for recordation;

Figure 2 is a vertical cross-sectional view of the same phonograph, taken substantially along the line 2—2 of Figure 1, but with the instrument adjusted for reproduction and illustrating partly in section portions of the carriage and sound box; and

Figure 3 is a view of the sound box portion of the phonograph in the condition of adjustment last above mentioned, together with an illustration of typical sound-dispersing means.

The general details of the phonograph in which my invention has been illustrated are best seen in Figures 1 and 2. Herein appears a base 1 supported on a cabinet C. The base is provided with suitable end standards, of which the left-hand one appears in Figure 2 as 2, and with an intermediate standard 3. Journalled in the standard 3 is a mandrel shaft 4, to which is secured a mandrel 5. The mandrel is adapted to removably support a cylindrical record blank 6, the latter being most conveniently hereinafter referred to as a "record," irrespective of the presence or absence of recorded matter thereon. The shaft 4, with mandrel 5 and record 6, is adapted to be rotated by suitable means not herein necessary to show.

Further in Figures 1 and 2 will be seen two rods

10 and 10' disposed parallel to the shaft 4 and supported between the end standards; along which rods is adapted to slide a carriage 11. On the forward part of the carriage 11 is mounted a sound-box 12, which is provided with a translating system including recording and reproducing tools or styli as hereinafter set forth. Ordinarily the recording tool, neither tool, or the reproducing tool may be engaged at will with the surface of the record 6 by adjusting an outwardly extending lever 15 to predetermined positions within a slot 16 formed in the top of carriage 11. These positions may be respectively identified as recording, neutral and reproducing positions. In the operation of the phonograph for recordation upon or reproduction from the record 6, the appropriate tool is intended to move longitudinally of the record while the latter is being rotated; accordingly the carriage 11 is appropriately moved along the rods 10 and 10'. To produce such movement there is provided a feed screw 17 parallel to the carriage supporting rods 10 and 10', journalled to the end standards; on this screw is secured the gear 18 engaging the gear 19 secured on the shaft 4. The feed screw 17 is adapted to be engaged by a feed nut 20 supported by the carriage 11, during which engagement the rotation of the feed screw will produce a rightward movement of the carriage as illustrated in Figure 1. The design is such that feed nut 20 engages the feed screw 17 at all times when the lever 15 is adjusted to either recording or reproducing positions, though when the lever is adjusted to neutral position the feed nut may be disengaged from the feed screw by means not necessary to be shown in these figures.

A brief description of some of the parts of the sound box may be presented as follows:

Two parallel lugs 106 are provided at the front of the sound box 12, extending downwardly from the main casing 12' of the sound box and slightly spaced on either side of the front and rear center line of the casing. These lugs support a horizontal pivot pin 107. Outside the lugs are pivoted to the pin 107 a pair of arms 108; these arms are secured to a diaphragm casing 109, which will be understood to contain a diaphragm (not shown) suitable for response to and propagation of sound waves through a flanged tube 110 and the neck 21 hereinafter mentioned. To the diaphragm, in manner suitable for actuation thereby and not necessary to describe in detail, is supported a recording tool mount 111 carrying at its lower extremity the recording tool or stylus 111. Between the lugs 106 there is pivoted to the pin 107

a bracket 112, to which there is in turn pivoted by a generally vertical pivot stud 113 a circular weight 114. To this weight is intermediately pivoted an arm 115 carrying at its lower extremity the reproducing tool or stylus 116. During normal operation of the phonograph for reproducing the diaphragm casing 109 is maintained in the illustrated position, wherein the recording tool 111 is raised substantially from the surface of record 6; at the same time the weight 114 is permitted to float on its double pivotal support (pin 107 and stud 113) and thus to urge downwardly the arm 115. Under these conditions the upper extremity of the arm 115 is engaged and supported by the recording tool mount 111', so that the floating weight 114 causes the reproducing tool 116 to press against the record surface; vibrations of the tool 116 are transmitted by the arm 115 to the tool mount 111' and therethrough to the diaphragm. During normal operation of the phonograph for recording the diaphragm casing 109 is lowered from the illustrated position so that the recording tool 111 bears against the record surface. This lowers the upper end of arm 115 and causes the reproducing tool 116 to rise from the record surface, the floating weight 114 thus being permitted to move toward the record surface until there contacts with the latter a smooth, small weight-supporting ball 114" secured to the bottom of the weight.

The assumption of the diaphragm casing 109 and the weight 114 of the outlined positions is normally controlled by two fingers 117 and 118, respectively adapted to impinge against and raise a lug 109' secured to the diaphragm casing 109 and a lug 114' secured to the weight 114. These fingers extend outwardly from the hub assembly 15' of the lever 15, which hub assembly surrounds the lever hub 15'; this hub in turn rotatively surrounds a cylinder 11' which slides along the rod 10 and forms a part of the carriage 11. When the lever 15 is moved to its most forward or recording position, both fingers 117 and 118 assume low positions, disengaging the respective lugs 109' and 114'; when the lever is moved to intermediate or neutral position, both the fingers 117 and 118 impinge upon and raise the respective lugs 109' and 114'; and when the lever is moved to its most rearward or reproducing position, finger 117 maintains lug 109' raised while finger 118 again assumes a low position of disengagement from lug 114', as illustrated in Figure 2. The outlined movements of the fingers 117 and 118 by the lever 15 are accomplished by mechanism disposed 55 within the hub assembly 15' and not herein necessary to describe.

Referring to Figure 2 it will be seen that the sound box 12 is provided with a cylindrical neck 21 through which sound waves pass, in recordation to and in reproduction from, lower portions of the sound box—i. e., in recordation inwardly and in reproduction outwardly. Swivellingly mounted with respect to this neck is a coupling member 22 having a central tubular portion 22' fitting about the neck 21, and having a cylindrical connecting portion 22'' disposed angularly with respect to the portion 22' and acoustically connected therewith by virtue of an orifice 22'''. To the connecting portion 22'' is attached a flexible sound conducting tube 23, at the outer extremity of which is provided a mouth-piece 24. In recordation sound is collected by the mouth-piece 24 and passes therefrom through the flexible tube 23 to the coupling member 22, and therethrough inwardly into the neck 21. It is possible, in the

use of the phonograph for reproduction, to permit the outwardly directed sound waves to pass from the neck 21, in precisely the reverse of the path just mentioned, to the mouth-piece 24; the mouth-piece then being employed as a sound dispersing means.

It will be appreciated that in the use of the phonograph for many purposes, including that of reproduction of dictation for transcription thereof, the mouth-piece forms a relatively unsatisfactory sound dispersing means. Accordingly one feature of the present invention is an arrangement whereby a set of ear-phones may, when desired, be conveniently connected with the sound-box 12 in such manner as to receive substantially all the sound waves passing outwardly through the neck 21. Such ear-phones and a flexible sound conducting tube therefor are illustrated in Figure 3 at 25 and 26 respectively; the arrangement for their connection with the sound-box 12, however, is illustrated in detail in Figure 2.

It will be seen, in Figure 2, that the top of the connecting portion 22'' of the coupling member 22 is provided with a boss 27. Extending through the boss 27 and in substantial alignment with the neck 21 is a hole 27', similar in diameter to the internal diameter of the neck 21. Through the hole 27' and into the neck 21 may be inserted the small tubular portion 31' of an adapter 31, this portion being preferably dimensioned to provide a good fit with said hole and neck. The adapter 31 has a larger tubular portion 31'' interiorly continuous with the smaller portion 31', and on such larger portion is formed a fluted tube connection 33. The top of the larger portion 31'' is closed, as for example by a knurled screw cap 34. The tube 26 (seen in Figure 3), being conveniently of rubber, is forced on to the connection 33. Thus when the adapter portion 31' is positioned as shown in Figure 2 sound waves passing outwardly through the neck 21 are guided interiorly of the adapter 31 to the tube connection 33, and therethrough and through the tube 26 to the ear-phones 25.

The adapter 31 is of course inserted in the illustrated position only when the phonograph is employed for reproduction, it being obvious that the portion 31' blocks the sound path between the mouth-piece 24 and the neck 21. This path is of course automatically cleared by removal of the adapter, but will then be characterized by an objectionable sound leakage unless the hole 27' is closed. Accordingly a cover 28 is provided for this hole and is biased to a normally closed position. The cover 28 may be pivoted to a short arm 29, as at 28', and the arm in turn pivoted to the boss 27 as by a pin 29'. The closing bias for the cover is provided by biasing the arm 29, as illustrated in Figure 2, to clockwise rotation, this being effected by a torsion spring 32 coiled about the pivot pin 29' and having terminals respectively impinging against the coupling member portion 22'' and hooked about the arm 29. In Figure 1 the cover 28 is shown in its closed position.

A significant possibility of damage to the record during transcribing operations is guarded against by the present invention, namely, the possibility of the engagement of the recording stylus with the record surface, by accidental movement of the lever 15 to its recording position. Such engagement of the recording stylus, it will be understood, would during record rotation be likely to obliterate matter already recorded on the record 75

and which it may be desired to transcribe. Accordingly the adapter 31, which is inserted in the hole 27' in the coupling member 22 when the phonograph is to be used in connection with transcription as above described, is provided with a curved arm 136 extending rearwardly from the junction of its smaller and larger tubular portions 31' and 31''. This arm is intended to extend partially over the slot 16 in carriage 11, and its function is to preclude adjustment of the lever 15 to a position forwardly of the neutral position—i. e., to prevent adjustment to recording position. There is conveniently provided on the top of carriage 11, to one side of the center of slot 16, a vertical member 11''. The lever 15 is in its neutral position when parallel with this member 11'', which therefore serves as a guide to adjustment of the lever. The end of the rearwardly extending arm 136 may advantageously be provided with a slight bifurcation 137 which, with the adapter properly in place, will engage the vertical guide member 11''. This secures the adapter 31 against rotation in its mounting and prevents consequent misalignment of the arm 136 with respect to the slot 16.

While I have illustrated and described my invention in terms of a particular embodiment thereof, it will be understood that thereby I intend to impose no unnecessary limitation, but rather intend to express the scope of my invention by the following claims.

I claim:—

1. In a phonograph, a sound-box including means for recording upon and reproducing from a record; a sound collecting device; means connecting said device with said sound-box and forming a sound conducting passage therebetween; sound dispersing means; and means, connected with said dispersing means and removably insertable into said passage, for substantially closing said passage and providing a sound conducting passage from said sound-box to said dispersing means.

2. In a phonograph, a sound-box including means for recording upon and reproducing from a record, said sound-box being provided with a sound conducting neck; a coupling member having a sound conducting portion inclined to and opening into said neck, said inclined portion being provided with a hole in alignment with said neck; a sound conducting member adapted for insertion through said hole and into substantial engagement with said neck; and sound collecting and sound dispersing means, one of said last

mentioned means being connected with said inclined portion and the other with said sound conducting member.

3. In a phonograph, a sound-box including means for recording upon and reproducing from a record; a sound collecting device; means connecting said device with said sound-box, forming a sound conducting passage therebetween, and intermediately provided with an aperture leading into said passage; sound dispersing means; a sound conducting member connected with said dispersing means and adapted for insertion through said aperture and into said passage to connect said sound dispersing means with said sound-box; and aperture closing means biased to close said aperture when said sound conducting member is removed therefrom.

4. In a phonograph, a translating system adapted for cooperation with a record; means for adjusting said system selectively for recordation and reproduction; a sound collecting device; means normally connecting said device with said translating system; sound dispersing means; means, connected with said dispersing means and removably insertable in said connecting means, for connecting said dispersing means with said translating system; and means, operative when said adapter is so inserted, for restricting the possible operative adjustments of said translating system.

5. In a phonograph, a sound-box including means for recording upon and reproducing from a record; a lever connected with said sound-box and movable to adjust said sound-box selectively for recordation and reproduction; a sound collecting device; means connecting said device with said sound-box and forming a sound conducting passage therebetween; sound dispersing means; an adapter connected with said dispersing means and removably insertable into said passage for connecting said sound-box with said dispersing means; and an arm carried by said adapter and extending, when said adapter is so inserted, into the path of movement of said lever whereby to restrict the possible movement thereof.

6. In a phonograph, translating means for recording upon and reproducing from a record; a sound collecting device; means operatively connecting said device with said translating means; sound dispersing means; and means, connected with said dispersing means and removably insertable into said connecting means, for connecting said translating means with said dispersing means.

HEINRICH F. MAX GRAMANN. 55
